UNITED STATES PATENT OFFICE.

GUILFORD D. ROWELL, OF APPLETON, WISCONSIN.

FEED-MILL.

SPECIFICATION forming part of Letters Patent No. 402,618, dated May 7, 1889.

Application filed October 15, 1888. Serial No. 288,130. (No model.)

To all whom it may concern:

Be it known that I, GUILFORD D. ROWELL, of Appleton, in the county of Outagamie and State of Wisconsin, have invented new and useful Improvements in Feed-Mills; and I do hereby declare the following to be a full, clear, and exact description of said invention, reference being had to the accompanying drawings, and to the letters or figures of reference marked thereon, which form a part of this specification.

My invention relates to improvements in feed-mills, and it pertains to the peculiar construction and arrangement of the several details hereinafter referred to, and the same are explained by reference to the accompanying drawings, in which—

Figure 1 represents a perspective view of my machine. Fig. 2 is a horizontal section drawn on line X X of Fig. 1. Fig. 3 is a vertical section drawn on line Y Y of Fig. 2. Fig. 4 is a detail showing the device for adjusting the feed-gate. Fig. 5 is a detail showing the device for adjusting the stationary grinding-burr to conform to the surface of the rotating grinding-burr. Fig. 6 represents the stationary grinding-burr removed from the machine. Figs. 7 and 8 are details showing the manner of adjusting the journal-bearings at the respective ends of the auxiliary driving-shaft. Fig. 9 is a detail showing one end of the feeding mechanism.

Like parts are represented by the same reference-letters throughout the several views. The general construction and arrangement of the stationary grinding-burr A and the rotating grinding-burr B within the chamber C, and the feed mechanism D and E, by which the feed is forced forward from the receptacle F and hopper F' between the grinding-surfaces of the burrs, are constructed substantially in the ordinary way.

H is an adjusting-screw, supported at its outer end in a loosely-fitting aperture, I, and at its inner end in a screw-threaded friction-bearing or nut, J, which nut J is held rigidly in place by its frictional contact with the bearing-surface K upon one side and the adjusting-screw L upon its opposite side. The friction of the bearing-surfaces upon the nut J is sufficient to hold it in place for ordinary grinding; but when the burrs meet with an

obstruction which would otherwise break them the friction-bearing or nut J is forced outward, thus permitting the burrs to separate from each other. The screw H is turned toward the right and left through the nut or friction-bearing J, as may be required in adjusting the grinding-burrs for grinding coarse or fine feed.

M are movable blocks or bearing-surfaces, which are interposed between the end of the shaft G and the adjusting-screw H. The stationary grinding-burr is supported upon one side by stationary pivot N and upon the opposite side by an adjustable pivot, O, which pivot O is supported and adjusted by the three adjusting-screws P P, as shown in Fig. 5, whereby it is obvious that the vertical sides of the stationary burr may be adjusted to conform to the surface of the rotating burr. The lower side of the stationary burr is provided with a downward-projecting lug, R, which is located between the adjusting-screws S S. Thus it is obvious that the horizontal surfaces of the stationary burr may be inclined in either direction toward or from the rotating burr by turning the adjusting-screws S, and as said adjustment is produced said stationary burr turns upon its pivots N and O. Thus by the two sets of adjusting-screws P and S the stationary burr may be adjusted to conform to the surface of the rotating burr. By my improvements the feed-gate T is located at the bottom of the feed-chamber, and it extends downward past the sides of the driving-shaft C, and it is provided with guide-ways d d, formed therefor in the respective sides of the chamber F, and with a slot, 1, formed in its lower edge for the reception of the shaft G. In Fig. 3 the feed-gate T is shown in its raised or open position, in which position the feed is forced beneath it.

Located beneath the shaft G is a vertical partition, 2, which is adapted to close the aperture 1, formed in the gate T, when said gate is closed, whereby the feed is prevented from passing to the grinding-burrs beneath the shaft. The gate T is provided with an upward-projecting arm, 3, having a series of gear-teeth, 4, into which the teeth of the pinion 5 are adapted to mesh. The pinion 5 is rigidly affixed to the shaft 6 and turns with it.

To one of the protruding ends of the shaft

6 is affixed a hand-wheel, 7, by which the pinion 5 is turned. When the hand-wheel 7 is turned in one direction the gate T is raised, and when turned in the opposite direction it is closed. A spiral spring, 9, is interposed between the bearings of the hand-wheel 7 and one of the shaft-supporting lugs 10, which, by its frictional contact with said hand-wheel, prevents it from being turned by the weight 10 of the feed-gate. Thus the gate is held by the friction of said spring 9 at any point of adjustment desired. As shown in Fig. 9, the spiral feed-flanges E are formed in two parts, *a a*, which parts taper outwardly from the 15 cylinder 11, to which they are attached to their ends at *b b*, whereby any foreign substances of greater dimensions than that of the grain which is being ground are permitted to enter beneath and are crushed by them as they 20 rotate.

13 is an auxiliary shaft, by which the mill may be connected by ordinary couplings and a tumbling-rod with a horse or other power. When the mill is operated by a tumbling-rod, 25 as mentioned, motion is communicated from the shaft 13 to the driving-shaft G of the mill through the gear-wheels 14 and 15. The shaft 13 is supported at its respective ends by the end frames, 16 and 17, in the adjustable journal-bearings 18, which bearings are supported 30 by the adjusting-screws 20 20. The journal-bearings 18 are formed alike at both ends of the shaft 13, and are fully illustrated in Figs. 7 and 8.

35 Having thus described my invention, what I claim as new, and desire to secure by Letters Patent, is—

1. In a feed-mill, the combination of the

driving-shaft G, the thereon-supported grinding-burr B, adjusting-screw H, friction bearing-block J, and block-retaining screw L, all substantially as and for the purpose specified. 40

2. In a feed-mill, the combination of the feed-chamber F, provided with gate-retaining guideways D D, feed-gate T, provided at its 45 lower end with a central recess, 1, for the reception of the driving-shaft, vertical partition 2, located below said shaft and adapted to close the lower end of said recess 1 beneath the shaft, and means, substantially as described, for adjusting said feed-gate, substantially as and for the purpose specified. 50

3. In a feed-mill, the combination of the feed-chamber F, provided with gate-retaining guideways d d, feed-gate T, provided at its 55 lower end with a central recess, 1, for the reception of the driving-shaft, vertical partition 2, located below said driving-shaft and adapted to close the lower end of said recess 1 beneath the shaft, upward-projecting arm 3, provided 60 with series of cog-teeth 4, shaft 6, supported in journal-bearings at its respective ends from the burr-inclosing case, pinion 5, affixed to said shaft 6 and meshing in the cogs of said arm 3, hand-wheel 7, affixed to one of the protruding ends of said shaft 6, and spiral spring 9, interposed between said hand-wheel and one of said shaft-supporting bearings, all substantially as and for the purpose specified. 65

In testimony whereof I affix my signature in presence of two witnesses. 70

GUILFORD D. ROWELL.
